UNITED STATES PATENT OFFICE

125,122

DESIGN FOR A CIGARETTE TIP

Paul H. Urben, Pittsburgh, Pa.

Application May 11, 1940, Serial No. 92,307

Term of patent 3½ years

To all whom it may concern:

Be it known that I, Paul H. Urben, a citizen of the United States, residing at Pittsburgh, in the county of Allegheny and State of Pennsylvania, have invented a new, original, and ornamental Design for Cigarette Tips, of which the following is a specification, reference being had to the accompanying drawing, forming part thereof.

In the drawing:

Fig. 1 is a perspective view of a cigarette tip showing my new design;

Fig. 2 is a side elevational view; and

Fig. 3 is an end elevation thereof looking from the right end of Fig. 2.

I claim:

The ornamental design for a cigarette tip, substantially as shown.

PAUL H. URBEN.
